ESCUTCHEON PLATE FOR CABINETS AND THE LIKE

Leland George Stone, Mundelein, Ill., assignor to Amerock Corporation, Rockford, Ill., a corporation of Illinois

Filed July 15, 1966, Ser. No. 3,082

Term of patent 14 years

(Cl. D10—8)

FIG. 2 is a perspective view of the escutcheon plate for cabinets and the like.

FIG. 3 is a top view.

FIG. 4 is a sectional view taken along the line 4—4 in FIG. 1.

I claim:

The ornamental design for an escutcheon plate for cabinets and the like, substantially as shown.
